(57) **CLAIM**

The ornamental design for the impact tool, as shown and described.

DESCRIPTION

FIG. 1 is a perspective view of the impact tool showing my new design;

FIG. 2 is a right side view of the impact tool of FIG. 1, the left side view being a mirror image thereof;

FIG. 3 is a front view of the impact tool of FIG. 1;

FIG. 4 is a rear view of the impact tool of FIG. 1;

FIG. 5 is a top view of the impact tool of FIG. 1; and,

FIG. 6 is a bottom view of the impact tool of FIG. 1.

The broken lines in the drawing represent unclaimed portions of the impact tool.
